TABLE LEG

Morton R. Cohen, Chicago, Ill.

Application March 11, 1957, Serial No. 45,202

Term of patent 14 years

(Cl. D33—14)

Fig. 1 is a perspective view of a table leg showing my new design;

Fig. 2 is an elevational view of the same on an enlarged scale;

Figs. 3, 4, 5 and 6 are sectional views taken along the lines 3—3, 4—4, 5—5 and 6—6, respectively, of Fig. 2 and in the indicated direction.

The dotted lines shown in Figs. 1 and 2 are for illustrative purposes only.

The design is characterized principally by the formation of the ornamental sleeve with perforations.

I claim:

The ornamental design for a table leg, substantially as shown and described.
